UNITED STATES PATENT OFFICE.

JOHN C. REAVES, OF PLYMOUTH, CALIFORNIA.

TAPPET.

1,405,719.

Specification of Letters Patent.

Patented Feb. 7, 1922.

Application filed June 2, 1920. Serial No. 386,117.

To all whom it may concern:

Be it known that I, JOHN C. REAVES, a citizen of the United States, residing at Plymouth, in the county of Amador, State 5 of California, have invented certain new and useful Improvements in Tappets; and I do declare the following to be a full, clear, and exact description of the same, reference being had to the accompanying drawings, 10 and to the characters of reference marked thereon, which form a part of this application.

This invention relates to improvements in tappets of the kind universally used in connection with ore-stamps, the principal object being to provide a tappet of the gib and key type which may be positively and easily locked to the shaft or stem of the stamp at any predetermined point thereon 20 and which is readily loosened to adjust its position on the shaft.

Another object is to so arrange and construct the parts of the tappet, that the frictional engagement of the shaft therewith will extend with even pressure over a greater part of the height of the tappet, so that it will cling to the shaft with less cinching up to withstand the heavy strain incident to its use than is necessary with the 30 ordinary type of gib and key tappet, in which the binding engagement with the shaft is had only at a plurality of points instead of over a continuous area.

It is this defect in the design of the present style of tappet that causes them to fracture around the keyways, since on account of limitations of space, the surrounding metal cannot be made of a thickness sufficient to long withstand the wedging strain 40 and the constant hammering of the actuating cams.

I feel that with my improved form of tappet, I have overcome the objectionable features pointed out above, and yet the entire structure will be no more bulky or 45 weighty than the present forms.

A further object of the invention is to produce a simple and inexpensive device, and yet one which will be exceedingly effective for the purposes for which it is designed.

These objects I accomplish by means of such structure and relative arrangement of parts as will fully appear by a perusal of 55 the following specification and claims.

In the drawings similar characters of reference indicate corresponding parts in the several views.

Fig. 1 is a side elevation of the tappet, in engagement with a shaft.

60

Fig. 2 is a vertical section thereof.

Fig. 3 is a cross section on a line 3—3 of Fig. 1.

65

Fig. 4 is a vertical section taken on a line 4—4 of Fig. 2.

70

Fig. 5 is an elevation of one of the gibs 10.

Referring now more particularly to the characters of reference on the drawings, the numeral 1 denotes the body of the tappet in general, consisting of a sleeve 2 at each end of which are enlarged portions 3 hardened on their outer ends and adapted to receive the actuating cam of the stamp-mill thereagainst.

Between the members 3 on one side of the 75 sleeve is a boss 4, which extends flush with the outer surface of the members 3, in order to provide sufficient metal for my purpose.

The body 1 is bored lengthwise for the reception of the shaft or stem 5, that half of the bore adjacent the boss being on a center eccentric from the center of the stem and toward the boss, so that on that side a clearance is had between the stem and the bore, 80 as shown at 6.

Cut or cored in the boss 4 lengthwise of the shaft is a pocket 7, whose sides are parallel, and the back of which tapers toward the shaft from the center to the ends.

A transverse straight keyway 8 in the 90 boss cuts through this pocket central of its length, being open at each end. Similar but smaller keyways 9 are positioned at each end of the pocket.

Slidable in the pocket are similar but opposed gibs 10 one face of the same being tapered as at 11 to contact with the tapered wall of the pocket, and the opposed face being concavely curved as at 12 to fit around the shaft 5 and having the same curvature 100 thereof.

The adjacent ends of the gibs are spaced apart somewhat even when they are loosened, and such ends then project into the keyway 8 and are tapered in opposite directions as 105 shown at 13 to form a wedge-shaped seat therebetween to receive the similarly tapered edges of a driving key 14 thereagainst. The initial portion of this key however is tapered to a greater degree than the remainder, 110

as shown at 15, since when first driving the gib 5 apart not so much force is necessary as when they are nearly snug on the shaft, and hence the initial movement thereof may be quicker.

The opposite ends of the gib 5 are also tapered as at 16 and project into the keyways 9, such tapered edges being parallel to the other tapered edges 13, so that while 10 the key 14 is driven in from one side of the boss to tighten the gib 5, the loosening keys or drifts such as are commonly used for the purpose, must be driven in from the opposite side.

15 In operation then, to loosen the tappet, a man on one side thereof strikes on the key 14 to retract the same, and from the same side drives in the gib-loosening drifts, when the tappet may be adjusted on its stem. A 20 man on the other side of the tappet then knocks out the drifts and hammers the driving key 14 back into place to force the gib 5 apart. The wide ends of the members 10 are flattened transversely as at 11^a, or parallel to 25 the bore thereof, in order to provide ample clearance from the walls of the keyway 8.

From the foregoing description it will be readily seen that I have produced such a device as substantially fulfills the object of 30 the invention as set forth herein.

While this specification sets forth in detail the present and preferred construction of the device still in practice such deviations from such detail may be resorted to as do not 35 form a departure from the spirit of the invention, as defined by the appended claims.

Having thus described my invention what I claim as new and useful and desire to secure by Letters Patent is:—

40 1. A tappet comprising a body bored to surround a shaft, a pocket formed in the body lengthwise thereof communicating with the bore and whose inner edge tapers towards the bore from central of its length toward 45 the ends, similarly tapered gib 5 slidably seated in the pocket shaped to partially encircle the shaft, the adjacent ends being oppositely tapered relative to each other, a tapered driving key adapted to be inserted 50 between such tapered ends to force the gib 5 apart, and transverse keyways at the ends of the pocket, the opposite ends of the gib 5

projecting thereinto and being tapered parallel to the other end thereof, whereby to loosen the gib 5 when driven apart by the 55 key, drifts must be driven into the keyways from the side thereof opposite to the direction of driving of the key.

2. A tappet comprising a body bored to surround a shaft, a pocket formed in the body lengthwise thereof communicating with the bore and whose inner edge tapers towards the bore from central of its length toward the ends, similarly tapered gib 5 slidably seated in the pocket shaped to partially encircle the shaft, a transverse keyway in the body cutting through the pocket central of its length and into which the adjacent ends of the gib 5 project, a key adapted to be inserted into the keyway from one side thereof to force the gib 5 apart, and transverse keyways at each end of the pocket and into which the gib 5 protrude, these ends of the gib 5 being tapered so as to be engaged by drifts inserted into the latter keyways from 75 the direction opposite to that of the insertion of the key.

3. A tappet comprising a body bored to surround a shaft, a pair of gib 5 mounted in the body adjacent the bore and in longitudinally opposed order, being adapted to engage the shaft when forced apart and the adjacent ends thereof being oppositely tapered, and a double-tapered key adapted to be driven between the gib 5, the initial end 80 of the key for a distance approximately one-quarter of its length having a greater degree of taper than the remainder.

4. A tappet comprising a body bored to surround a shaft, a pair of gib 5 mounted in the body adjacent the bore and in longitudinally opposed order, being adapted to engage the shaft when forced apart, a key adapted to be driven between the gib 5, transverse keyways in the body at the opposite 90 ends of the gib 5 and into which the latter protrude, these ends of the gib 5 being adapted to be engaged by drifts inserted into the keyways to loosen the gib 5, and means whereby such drifts must be inserted 95 from the opposite side of the body from which the key is driven between the gib 5.

In testimony whereof I affix my signature.

JOHN C. REAVES
